ULTRA SHORT WAVE COMMUNICATION SYSTEM

Clarence W. Hansell, Port Jefferson, N. Y., assignor to Radio Corporation of America, a corporation of Delaware

Application June 2, 1933, Serial No. 673,974

10 Claims.

(Cl. 250—9)

This invention relates to ultra short wave communication systems and more particularly to such of these systems which utilize waves of less than one meter.

5 An object of the present invention is to provide a highly efficient and simple communication system for the transmission of centimeter waves.

A further object is to enable the simultaneous transmission and reception of such ultra short 10 waves by means of a common oscillator and reflector system.

A feature of the present invention is the reflecting system utilized which comprises two reflectors, one of a parabolic type and the other a 15 hemi-spherical reflector located in the focus of the parabolic reflector and arranged to direct energy into said parabolic reflector. These reflectors are arranged upon a pivoted support by means of which transmission and reception may 20 be carried out in any desired direction.

A further feature is the means employed to prevent interaction between the transmitting and receiving circuits of the system.

In brief, the invention comprises an ultra high 25 frequency oscillator, for example, a Barkhausen oscillator, the radiating elements of which are located at the center of a hemi-spherical reflector and in the focus of and facing towards a parabolic reflector. This oscillator is arranged to 30 produce radiation and, in practice, will ordinarily utilize the energy feed lines as the oscillatory circuit on which standing waves are allowed to develop. For transmission purposes, the hemi-spherical reflector catches all the radiation going 35 out in a more or less forward direction and sends it back towards the center of the oscillator system so that it will fall upon the parabolic reflector as if it had come directly from the oscillator. By properly dimensioning the two reflectors, all of the radiation is caught by the 40 reflector system and reflected from the parabolic reflector in the desired direction. Thus there is no leakage of energy due to radiation missing the reflector and maximum directivity is obtained.

45 It is proposed to modulate the output of the oscillator by varying the potential on its electrodes in any suitable manner.

The same system may also be used for reception 50 by causing any energy falling upon the reflector to be impressed upon the oscillator circuits and thus give rise to a variation in the input electrode currents to the oscillator.

A more complete understanding of the invention may be had by referring to the following 55 detailed description which is accompanied by

drawings, wherein Figure 1 illustrates a complete ultra short wave communication system for effecting simultaneous transmission and reception at a single point in accordance with the principles of the present invention, and Figure 2 5 illustrates a modification thereof wherein there is utilized a Wheatstone bridge or hybrid coil arrangement for aiding in preventing interaction between the transmitter and receiver of the reflector system.

10 Referring to Figure 1 in more detail, there is shown, schematically, a Barkhausen oscillator 1, the effective radiating center of which is located at the center of a hemi-spherical reflector 2 and in the focus of a parabolic reflector 3, both being 15 pivotally mounted at 20 and 21 for movement in any desired direction. Hemi-spherical reflector 2 is arranged to direct energy received by it back toward the parabolic reflector 3 from which radiation is reflected in the desired direction. A source 20 of potential 4 is provided for supplying a relatively high positive potential to the grid of the Barkhausen oscillator, and a source of potential 5 acts to supply a small negative potential to the anode thereof. This anode may be either at a 25 negative potential, as shown, or else at a small positive or even at the same potential as the cathode. For tuning the tube leads, there is provided a group of bypass condensers 6 in which adjustable taps on each of the tube leads serve to 30 join all the leads together for radio frequency currents, and still leave each lead of correct length for optimum oscillating conditions. The oscillations generated in the Barkhausen oscillator 1 are caused to exist as standing waves on 35 portions of the leads extending from the electrodes of the oscillator 1 through the parabolic reflector 3 to the sources of potential 4 and 5.

40 For modulating the oscillations, there is provided any suitable signal modulating means, such as a microphone 7, which is coupled to audio frequency transformer 10 through an amplifier 8 over any suitable transmission line, such as a telephone line 9, the currents in the secondary of transformer 10 being arranged to vary the 45 grid potential on the Barkhausen oscillator and thus also vary the strength of the oscillations. The variations in strength of the oscillations will be detected at a distant receiving station. If desired, both the grid and anode potentials 50 may be modulated in order to obtain amplitude modulation independent of frequency modulation or, in some cases, frequency modulation independent of amplitude modulation. One such method of obtaining modulation is described in 55

U. S. Patent 1,938,749, granted December 12, 1933, to N. E. Lindenblad.

The system indicated may also be used for reception since any energy falling upon the parabolic reflector 3 and being impressed upon the oscillator circuits will give rise to a variation in input current to the oscillator by adding to and opposing the local oscillations. If the transmitter from which it is desired to receive a communication has its frequency made somewhat different than the oscillator shown in the drawings, then the electrode input current will vary periodically at a rate corresponding to the difference between the two frequencies and these variations will have 10 an amplitude substantially proportional to the strength of the received radiation. Preferably, the beat between the carrier of the transmitter to be received and that of the oscillator shown in the figure should be at some frequency higher than audibility. It might, for example, be 20 1,000,000 cycles per second. By means of a tuned circuit 11 inserted in series with the lead to the grid there can be selected this one million cycle beat, and the energy from this circuit may be 25 coupled through an intermediate frequency receiver 13 to an ordinary loudspeaker or telephone receiver 12 for enabling the reception of the modulation of the distant transmitter. The system may be employed for receiving communications 30 from any one of a number of distant transmitters operating near the same frequency by simply tuning the intermediate frequency receiver for the beat frequency between the distant transmitter and the local ultra short wave oscillator. 35 Of course, if the distant transmitters are located in different directions the reflector must be turned on its pivot to selectively receive from the desired direction.

In the circuit shown, the intermediate frequency tuned circuit 11 has negligible impedance 40 for the audio input energy transmitted over line 9 and transformer 10, and permits the modulation of the oscillator due to this audio energy without any impediment. Audio transformer 10 45 is designed to present a low impedance to the 1,000,000 cycle beat frequency, and the secondary winding thereof may, if desired, be shunted by a bypass condenser 15 which has relatively low reactance for the intermediate frequency. In the 50 arrangement indicated it is possible that modulation of the oscillator for transmission purposes may cause some variation in the strength of the intermediate frequency impressed upon the intermediate frequency receiver 13, though, in general, there is a tendency for the intermediate 55 frequency energy to be independent of the strength of the local oscillations over a considerable range. In any case its only effect is to make a speaker's voice audible in his own receiver and 60 this is not objectionable since it is the common condition in almost all telephone circuits.

If it is desired to prevent the audio input energy impressed by amplifier 8 upon line 9 and transformer 10 from being reproduced through the 65 intermediate frequency receiver 13, an arrangement such as is indicated in Figure 2 may be employed wherein a hybrid coil is used. This hybrid coil is in the nature of a Wheatstone bridge which permits combining outgoing and incoming energies into a single circuit without permitting the outgoing energy to return again to the transmitter via the receiver in a manner to 70 set up spurious oscillations or singing.

In Figure 2 microphone 7 is shown connected in 75 parallel with a telephone receiver 12 across the

common telephone transmission line 9 which, in turn, is connected to the ends of two windings 16 and 17 of a hybrid coil 23. The opposite ends of the windings are connected to an impedance Z which simulates or matches the electrical constants of the telephone line. From the center of windings 16 and 17 connections are made to the input terminals of the transmitter amplifier 8. A second winding or pair of windings 18 and 19 on the hybrid coil are connected to the output 10 of the intermediate frequency receiver 13.

With the arrangement shown in Figure 2, when the adjustments are correct, output energy from the receiver cannot enter the transmitter, but half of the energy is transmitted over the wire 15 line 9 to the operator's receiver 12. The telephone transmitter currents are likewise prevented by the hybrid coil 23 from entering the receiver output circuit, but this is not important inasmuch as the receiver is a unilateral device and cannot 20 cause singing due to reversed energy transmission through it.

The foregoing invention is arranged to provide a highly efficient communication system at extremely low wave lengths of less than one meter 25 with excellent power output and may be used for such purposes as communication between ships in a harbor, between ships of a fleet, for relatively short distance communication between individuals, between buildings, across streams, 30 etc.; in fact, the invention may be used wherever the relative cheapness of a single system would be an advantage for both transmission and reception.

I claim:

1. An ultra short wave communication system for the simultaneous transmission and reception of electromagnetic energy comprising a wave reflecting surface formed to approximate a paraboloid and a hemi-spherical reflector mounted in the 40 focus of said reflecting surface and arranged to direct energy toward said surface, a Barkhausen oscillator comprising a cathode, anode and control electrode mounted in the center of said hemi-spherical reflector, said control electrode being at 45 a high positive potential with respect to said anode and cathode, sources of potential for said electrodes, energy feed leads extending from said oscillator through said reflecting surface to said sources, signal modulating means coupled to the 50 electrodes of said oscillator, and receiving apparatus also coupled to said electrodes.

2. An ultra short wave communication system for the simultaneous transmission and reception of electromagnetic energy comprising a parabolic 55 reflector and a hemi-spherical reflector mounted in the focus of said parabolic reflector and arranged to direct energy toward said parabolic reflector, a Barkhausen oscillator comprising a cathode, anode, and control electrode mounted in 60 the center of said hemi-spherical reflector, said control electrode being at a high positive potential with respect to said anode and cathode, sources of potential for said electrodes, energy feed leads extending from said oscillator through said parabolic reflector to said sources, signal modulating means coupled to the electrodes of said oscillator, receiving apparatus also coupled to said electrodes, and a Wheatstone bridge arrangement 65 coupled to said energy feed leads for preventing 70 undesirable reaction between said transmitter and receiver.

3. An ultra short wave communication system for the simultaneous transmission and reception of electromagnetic energy comprising a parabolic 75

- reflector and a hemi-spherical reflector mounted in the focus of said parabolic reflector and arranged to direct energy toward said parabolic reflector, an oscillator comprising a cathode, anode, and control electrode mounted in the center of said hemi-spherical reflector, said control electrode being at a high positive potential with respect to said anode and cathode, sources of potential for said electrodes, energy feed leads extending from said oscillator through said parabolic reflector to said sources, signal modulating means coupled to the electrodes of said oscillator, a parallel tuned circuit tuned to an intermediate frequency coupled to said oscillator, an intermediate frequency receiver connected to said parallel tuned circuit, an acoustic device, said intermediate frequency receiver being arranged to supply audio frequencies to said acoustic device.
4. An ultra short wave communication system for the simultaneous transmission and reception of electromagnetic energy comprising a parabolic reflector and a hemi-spherical reflector mounted in the focus of said parabolic reflector and arranged to direct energy toward said parabolic reflector, a Barkhausen oscillator comprising a cathode, anode, and control electrode mounted in the center of said hemi-spherical reflector, said control electrode being at a high positive potential with respect to said anode and cathode, sources of potential for said electrodes, energy feed leads extending from said oscillator in a direction along the focal line of said parabolic reflector to said sources, signal modulating means coupled to the electrodes of said oscillator, and receiving apparatus also coupled to said electrodes.
5. An ultra short wave radio communication system for the simultaneous transmission and reception of waves below one meter comprising a single oscillator for both transmission and reception, a reflector, said oscillator being at the focus of said reflector, and feed leads having standing waves thereon extending along the focal line of said reflector from the electrodes of said oscillator to energy supply means.
6. An ultra short wave radio communication system for the simultaneous transmission and reception of waves below one meter having, in combination, a parabolic reflector arrangement pivoted so as to be capable of motion for directive action in any desired direction, and an oscillatory system extending along the focal line of said parabolic reflector comprising an electron discharge device oscillator and leads from said oscillator through said reflector, and means for producing standing waves on said leads.
7. An ultra short wave radio communication system for the simultaneous transmission and reception of waves below one meter having, in combination, a parabolic reflector and a hemi-spherical reflector arranged to direct energy toward said parabolic reflector, and an oscillatory system extending along the focal line of said parabolic reflector comprising an electron discharge device oscillator and leads from said oscillator through said reflector, and means for producing standing waves on said leads.

cal reflector arranged to direct energy toward said parabolic reflector, and an oscillatory system whose effective center is at the focus of both of said reflectors and which extends along the focal line of said reflectors through said parabolic reflector to an energy translating device.

8. An ultra short wave radio communication system for the simultaneous transmission and reception of waves having, in combination, a parabolic reflector and a hemi-spherical reflector arranged to direct energy toward said parabolic reflector, and an oscillatory system whose effective center is at the focus of both of said reflectors, said oscillatory system comprising a single electron discharge device having an anode, cathode, and control electrode, leads for said electrodes extending through said parabolic reflector to energy supply means for maintaining said control electrode at a positive potential relative to the cathode and anode, and signal modulating means in circuit with said electrodes whereby there are caused to exist standing waves on said leads, said reflectors being pivotally mounted for directive action on the arc of a circle.

9. An ultra short wave radio communication system for the simultaneous transmission and reception of waves having, in combination, a parabolic reflector and a hemi-spherical reflector arranged to direct energy toward said parabolic reflector, and an oscillatory system whose effective center is at the focus of both of said reflectors and which extends along the focal line of said reflectors at least up to said parabolic reflector, a transmitter and a receiver in circuit with said oscillatory system, said receiver having means for selectively receiving the beat frequency between the oscillations generated by said oscillatory system and the received waves, and a balancing circuit for preventing undesirable reaction between the transmitted and received modulation currents.

10. An ultra short wave communication system for the transmission and reception of electromagnetic energy below one meter comprising a parabolic reflector and a hemi-spherical reflector mounted in the focus of said parabolic reflector and arranged to direct energy towards said parabolic reflector, a radiating system at the focus of both said reflectors comprising a multi-electrode electron discharge device oscillator whose control electrode is at a high positive potential relative to its cathode, and feed leads having standing waves thereon extending from the electrodes of said device along the focal line of said reflector through said parabolic reflector to energy supply means, signal modulating means coupled to the electrodes of said oscillator and receiving apparatus also coupled to said electrodes.

CLARENCE W. HANSELL.
